(57) **CLAIM**

The ornamental design for a handguard as shown and described.

DESCRIPTION

FIG. 1 is a perspective view of a handguard showing the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The evenly spaced lines depict portions of the handguard that form no part of the claimed design. The long-dash/short-dash broken lines depict the boundaries of the handguard and form no part of the claim. The unshaded portions between broken line types forms no part of the claimed design.
